BUFFING DEVICE FOR RAILWAY CAR
VESTIBULE DIAPHRAGMS

Peter Kass and George S. Goodwin, Chicago,
Ill., assignors to Union Metal Products Com-
pany, Chicago, Ill., a Corporation of Dela-
ware

Application August 1, 1930. Serial No. 472,345

17 Claims. (Cl. 105—10)

This invention relates to an improvement in a buffing device for the upper portion of a vestibule diaphragm such as is used on railway cars and like vehicles.

5 The main object of the invention is to provide a comparatively simple buffing device having ample strength to normally maintain the diaphragm fully extended so as to effect a tight joint between the face plates of adjacent vestibule diaphragms of connected cars. Other objects are: to provide a buffing device of the type described which will be mounted wholly outside of the car and outside of the diaphragm; to provide a buffing device of the type referred 10 to which will permit free pivotal movement of the end or face plate of the diaphragm, such as normally occurs, relative to the car end when a train of cars moves around a curve; and to provide a device having the above characteristics 15 20 25

which will also be sufficiently flexible or compressible to readily permit the normal full extent of contraction and expansion of the diaphragm without excessive wear or strain on the buffing device and without the production of objectionable noise.

Other objects and advantages of our invention will be understood by reference to the following specification and accompanying drawing in which we have illustrated a selected embodiment 30 35 40 45 50 55 60 65 70 75 80 85 90 95 100 105 110

In the drawing:

Fig. 1 is an end elevation of a portion of a railway car.

Fig. 2 is a cross section on the line 2—2 of Fig. 1.

Fig. 3 is a section on the line 3—3 of Fig. 2.

Fig. 4 is an illustration of the parts of our improved buffing device in disassembled relation.

Figs. 5 and 6 are plan and side views, respectively, of a modified arrangement of our improved buffing device.

Referring now to the drawing, we have indicated the end portion of a railway car at 5, a vestibule diaphragm at 6, and a diaphragm end or face plate at 7. The face plate 7, in the present instance, is illustrated as being in the form of an inverted U-shaped member, the lower ends 45 50 55 60 65 70 75 80 85 90 95 100 105 110

55 of the sides or legs thereof being secured to the lower buffer member 8 which is supported by means of supports 9—9 adjacent its ends.

The supports 9—9 may be of any desired form and each may be described broadly as including

55 a rod which is pivoted at its outer end to the

buffer member 8 and which is slidably mounted in suitable bearings carried by the frame-work of the car. The outer ends of such rods, while pivoted to the buffer plate 8, are also connected thereto so that the weight of the buffer plate 8 and the weight of the diaphragm end plate 7 are carried by the rods.

A center buffing device 10 is also provided for yieldingly urging the lower buffer member 8 to move outwardly from the end of the car. This lower buffing device may also be of any desired construction, and in this instance is illustrated as including a rod which is pivotally connected to the central portion of the buffer plate 8, as clearly shown in Fig. 1, so as to permit pivotal movement of the buffer plate 8 and diaphragm face plate 7 about the axis of the pivotal connection 11. The structure thus far described may be of any more or less standardized construction, which need not be more specifically described in this application since the details thereof are not involved in our present invention.

Our improved buffing device for the upper part of the diaphragm includes a conical spiral spring 12 which is preferably a so-called volute spring, this spring being interposed between the car end 13 and the central upper portion of the face plate 7 above the diaphragm 6. Preferably, the length of the spring 12 is substantially co-extensive with the distance between the car end and face plate so that a high degree of resiliency or flexibility is afforded. For positioning the spring 12, we provide mounting brackets or supports 14 and 15 which are respectively secured to the face plate 7 and car end 13, as clearly shown in Fig. 2.

The support 14 preferably consists of a tapered stud 16 which is carried by a mounting plate 17, the latter having openings through which rivets or bolts may pass for securing the support 14 to the face plate 7 as shown in Fig. 2. The stud 16, in this instance, is riveted in place in the plate 17, and the projecting end of the stud is of frusto-conical shape and is designed to enter the apex coil 18 of the spring 12.

The support 15 preferably consists of a socket member formed by a base part 19 and an annular flange 20 projecting laterally from the base 19. The base flange 19 is provided with suitably located apertures, as shown, to facilitate attachment of the bracket to the car end by means of rivets or bolts, as indicated in Fig. 2. The inside wall 21 of the socket is preferably inclined so that the socket is of greater diameter adjacent its outer end than at its inner end. The inner end portion of the socket is preferably of such diam-

eter that the base coil 22 of the spring will be effectively positioned and held against material lateral shifting movement.

The tapered stud arrangement 16 and the inclined or outwardly flaring wall 21 of the socket member permits relative pivotal movement between the spring and the mounting member 15 and between the mounting member 14 and the spring 12. Thus, it will be seen that the face plate 7 may rock about the apex end of the spring 12 as a fulcrum, while the face plate and spring may also rock as a whole about the base of the spring as a fulcrum. By this arrangement, limited lateral movement of the upper portion of the face plate 7 is also permitted and it will be understood that such movement, as well as pivotal movement of the face plate, about the more or less aligned axes formed by the hinge connection 11 and the apex end of the spring 12, may take place without materially distorting the spring so that there are no excessive strains placed upon the spring and no objectionable noises produced.

A highly important advantage found in the use of a conical spiral or volute spring in the arrangement described is that the spring may be compressed to a length equal to only the width of one coil. Also, in the arrangement shown, the stud 16 which fits inside of the apex and coil of the spring may telescope into the socket 21 and hence takes up no additional space. Therefore, it will be seen that a maximum working range is afforded as compared with the limited working range where ordinary coil springs are used, which, when compressed, are as long as the sum of the heights of all of the coils.

For limiting outward movement of the face plate 7, i. e., expansion of the diaphragm 6, we may provide flexible connections between the upper corners of the face plate 7 and the car end 13. In this instance, such connections are shown in the form of short two-link chains 23-23 which are of predetermined length sufficient to allow the full desired expansion of the upper portion of the diaphragm under the influence of the spring 12, while being capable of flexing or collapsing when the diaphragm is compressed under normal conditions. The chains are preferably located at the sides of the face plate so that they will not normally contact with the diaphragm 6.

50 In the modified arrangement shown in Figs. 5 and 6, the buffing spring and limiting means are incorporated in a unitary structure which may be assembled to form a complete unit which may be positioned as such between the car end and diaphragm face plate.

In this arrangement, the volute spring is interposed between and mounted at its ends on mounting brackets 24 and 25 in substantially the same manner as the spring is mounted on the brackets or plates 14 and 15. The bracket 24 at the apex end of the spring is provided with a pair of lugs or ears 26-26, between which a pivoting block 27 is mounted for vertical pivoting movement on a pivot pin 28 which extends through said ears and block. A link or arm 29, provided at one end with bifurcations 30-30 straddling the pivot block 27, is pivoted to the block by means of a pivot pin 31 extending vertically through said bifurcations and block.

70 Another link or arm 32 is pivotally connected or hinged on a horizontal axis to the link 29 at a point spaced from the end thereof as shown at 33. The other end of the link 32 is pivotally connected to the mounting bracket 25 by means of ears 34-34 formed integral with the bracket

and a pivot pin 35 which extends horizontally through the ears 34-34 and an eye formed in the end of the link.

The pivots at both ends of the link 32 are horizontally disposed and the outer end of the link 29 is mounted by means of the horizontally disposed pivot 28, so that the links are capable of buckling in a vertical direction when compression of the diaphragm takes place. In order to insure upward buckling of the links 29 and 32, a spring member 36 is interposed between the link 32 and the overlapping end portion 37 of the link 29. The spring 36 may be fastened in place in any suitable manner, for instance, by one or more rivets, such as indicated at 38.

As shown, the bifurcations 30-30 straddle the pivoting block vertically and the pivot pin 31 is vertically disposed so that the face plate on which the bracket 24 is adapted to be mounted is permitted to rock about a vertical axis as occurs under normal conditions without imparting undue horizontal swinging motion to the links. The pivoting block connection between the face plate and link 29 constitutes, in effect, a universal joint which permits unhampered relative movement between the face plate and the link.

It will be now understood that the structure shown in Figs. 5 and 6 is such that it may be completely assembled before being mounted on a car, and that the structure may conveniently and expeditiously be installed, as a unit, between a car end and a diaphragm face plate.

Our above described buffering mechanism, in addition to providing a maximum working range in which the face plate may move, is advantageous for the further reason that it is wholly on the outside of the car structure, and being wholly exposed is freely accessible for inspection and repair if needed.

We are aware that changes may be made in the above described construction without departing from the spirit of our invention, the scope of which should be determined by reference to the following claims, the same being construed as broadly as possible consistent with the state of the art.

We claim as our invention:

1. In a car vestibule construction, the combination with the car end, a relatively movable face plate, and an extensible diaphragm extending between and connected to said car end and face plate, of a conical spiral spring interposed between said car end and face plate for yieldingly maintaining said diaphragm expanded, and means for mounting the respective ends of said spring on said car end and said face plate comprising a stud secured to one of said parts for entering the apex coil of said spring, said stud fitting in said apex coil so as to permit relative pivotal movement between the stud-carrying part and the spring about the apex end of said spring, and means for mounting the base end of said spring on the other part comprising a bracket secured to said other part and having a projection for receiving the base coil of said spring.

2. In a car vestibule construction, the combination with the car end, a relatively movable face plate and an extensible diaphragm extending between and connected to said car end and face plate, of a conical spiral buffering spring interposed between the car end and the upper central portion of the face plate, and means

- on opposite sides of said spring for limiting expansion of said diaphragm by said spring.
3. In a car vestibule construction, the combination with a car end, a relatively movable face plate, and an extensible diaphragm extending between and connected at its ends to said car end and face plate, of a conical spiral spring interposed between the upper central portion of said face plate and said car end, means for mounting said spring on said face plate so as to permit relative pivotal movement between said spring and face plate, whereby the face plate end of said spring serves as a fulcrum for the normal rocking movement of said face plate, and means at the sides of said face plate for limiting expansion of said diaphragm by said spring. 80
4. In a car vestibule construction, the combination with a car end, a relatively movable face plate, and an extensible diaphragm extending between and connected at its ends to said car end and face plate, of a conical spiral spring interposed between the upper central portion of said face plate and said car end, means for mounting said spring on said face plate so as to permit relative pivotal movement between said spring and face plate, whereby the face plate end of said spring serves as a fulcrum for the normal rocking movement of said face plate, and a collapsible device extending between said brackets for limiting spreading thereof under the influence of said spring, thereby to limit expansion of said diaphragm. 85
5. In a car vestibule construction, the combination with the car end, a relatively movable face plate and an extensible diaphragm extending between and connected to said car end and face plate, of a conical spiral buffering spring interposed between the car end and the upper central portion of the face plate, supports for the ends of the spring fixed to the car end and face plate and arranged to permit limited relative pivotal movement between the spring and face plate, and collapsible link connections between the car end and the upper side portions of the face plate for limiting the movement of the latter away from the car end. 90
6. In a car vestibule construction, the combination with the car end, a relatively movable face plate, an extensible diaphragm extending between and connected to the car end and face plate, means for supporting the face plate arranged to permit contraction and expansion of said diaphragm longitudinally of the car and also rocking movement of said face plate about a vertical axis, of a conical spiral buffering spring interposed between the car end and the upper central portion of the face plate, supports for the ends of said spring fixed to the car end and face plate and arranged to permit limited relative pivotal movement between said face plate and spring, and collapsible link connections between the car end and the upper side portions of the face plate for limiting the movement of the latter away from the car end. 95
7. In a car vestibule construction, the combination with a car end, a relatively movable face plate and an extensible diaphragm extending between and connected to said car end and face plate, of a conical spiral spring interposed between said car end and face plate for yieldingly maintaining said diaphragm expanded, brackets respectively associated with the opposite ends of said spring and respectively mounted on said car end and face plate for supporting said spring in operative position, and a collapsible device extending between said brackets 100
8. In a car vestibule construction, the combination with a car end, a relatively movable face plate, and an extensible diaphragm extending between and connected at its ends to said car end and face plate, of a conical spiral spring interposed between the upper central portion of said face plate and said car end, a bracket secured to said car end and provided with means for supporting one end of said spring, a second bracket, secured to said face plate and having means for supporting the adjacent end of said spring so as to permit rocking movement of said face plate relative to said spring, whereby the face plate end of said spring serves as a fulcrum for the normal rocking movement of said face plate, and a collapsible device extending between said brackets for limiting spreading thereof under the influence of said spring, thereby to limit expansion of said diaphragm. 105
9. In a car vestibule construction, the combination with a car end, a relatively movable face plate and an extensible diaphragm extending between and connected to said car end and face plate, of a conical spiral spring interposed between said car end and face plate for yieldingly maintaining said diaphragm expanded, brackets respectively mounted on said car end and face plate and engaging the respective adjacent ends of said spring for supporting said spring in operative position, and a collapsible device extending between said brackets for limiting spreading thereof under the influence of said spring, thereby to limit expansion of said diaphragm, said device comprising a pair of links having adjacent ends pivotally connected together and their opposite ends respectively pivoted to said car end and face plate brackets, and means for yieldingly urging said links to buckle in a predetermined direction. 110
10. A buffering device for the upper end portion of the face plate of a railway car vestibule diaphragm construction, comprising a conical spiral spring, a pair of brackets respectively engaging the opposite ends of said spring and adapted to be mounted respectively on a car end and diaphragm face plate, and a collapsible device extending between and connected to said brackets for limiting spreading thereof by said spring while permitting compression of said spring between said brackets. 115
11. In a car vestibule construction, the combination with the car end and a relatively movable face plate, of a volute coil spring capable of being compressed into a minimum length substantially equal to the width of its base coil, means for mounting said spring between said car end and face plate comprising a bracket having a socket for receiving and positioning the base coil of the spring and a bracket having a stud entering the apex coil of said spring to position said apex end, said stud being capable of telescoping into said base coil receiving socket when the spring is compressed, and means to limit the forward movement of the face plate so as to retain the spring in operative engagement with said socket and stud, respectively. 120
12. In a car vestibule construction, the combination with a car end element, a relatively movable face plate element, an extensible diaphragm between said elements of a volute coil spring, a socket member attached to one of said elements which engages the exterior of the base of said 125
13. In a car vestibule construction, the combination with a car end element, a relatively movable face plate element, an extensible diaphragm between said elements of a volute coil spring, a socket member attached to one of said elements which engages the exterior of the base of said 130
14. In a car vestibule construction, the combination with a car end element, a relatively movable face plate element, an extensible diaphragm between said elements of a volute coil spring, a socket member attached to one of said elements which engages the exterior of the base of said 135
15. In a car vestibule construction, the combination with a car end element, a relatively movable face plate element, an extensible diaphragm between said elements of a volute coil spring, a socket member attached to one of said elements which engages the exterior of the base of said 140
16. In a car vestibule construction, the combination with a car end element, a relatively movable face plate element, an extensible diaphragm between said elements of a volute coil spring, a socket member attached to one of said elements which engages the exterior of the base of said 145

spring so as to resist lateral movement of the spring relative to the element, and a stud member attached to the other of said elements which engages the interior of the apex of said spring so as to resist lateral movement of the spring relative to the element.

13. In a car vestibule construction, the combination with a car end element, a relatively movable face plate element, an extensible dia-
10 phragm between said elements, of a volute coil
spring, a socket member attached to one of said
elements which engages the exterior of the base
of said spring so as to resist lateral movement of
the spring relative to the element, a stud mem-
15 ber attached to the other of said elements which
engages the interior of the apex of said spring
so as to resist lateral movement of the spring,
and means to limit the forward movement of
the face plate so as to retain the spring in oper-
20 ative engagement with the socket member and
stud member, respectively.

14. In a car vestibule construction, the combination with a car end element, a relatively movable face plate element, an extensible diaphragm
25 between said elements of a coil spring, a socket
member attached to one of said elements which
engages the exterior of one end of the spring so
as to resist lateral movement of the spring relative
30 to the element, and a stud member attached
to the other of said elements which engages the
interior of the other end of the spring so as to
resist lateral movement of the spring relative to
the element.

15. In a car vestibule construction, the combination with a car end element, a relatively movable face plate element, an extensible dia-
35 phragm between said elements of a coil spring,
a socket member attached to one of said elements
which engages the exterior of one end of the
40 spring so as to resist lateral movement of the

spring relative to the element, and a stud mem-
ber attached to the other of said elements which
engages the interior of the other end of the spring
so as to resist lateral movement of the spring
relative to the element, said socket and said stud
80 being tapered so as to permit relative pivotal
movement between the spring and the said mem-
bers, respectively.

16. In a railway car, the combination with a
car end element, a face element movable longi-
tudinally and laterally of the car to said end, a
coil spring interposed between the car end and
face plate, a socket member attached to one of
85 said elements which engages the exterior of one
end of said spring so as to resist lateral movement
of the spring relative to said element, and a stud
member attached to the other of said elements
which engages the interior of the other end of
90 said spring so as to resist lateral movement of
the spring relative to said element whereby the
lateral movement of the face plate relative to the
car end is yielding opposed by said spring.

17. In a railway car, the combination with a
car end element, a face plate element movable
longitudinally and laterally of the car to said end, a
convolute spring interposed between the car
end and face plate, a socket member attached
100 to one of said elements which engages the ex-
terior of one end of said spring so as to resist
lateral movement of the spring relative to said
element, and a stud member attached to the other
of said elements which engages the interior of
105 the other end of said spring so as to resist lateral
movement of the spring relative to said element
whereby the lateral movement of the face plate
relative to the car end is yieldingly opposed by
said spring.
